UNITED STATES PATENT OFFICE.

JAY G. SWAB, OF BROOKLYN, NEW YORK, ASSIGNOR TO HENRY TRENCHARD, JR., OF BROOKLYN, NEW YORK.

FLAP-TURNING MECHANISM.

Application filed May 16, 1923. Serial No. 639,279.

The present invention relates to machines for making envelopes and more especially to envelope machines of the so-called rotary type.

5   Rotary envelope machines commonly deliver the finished envelopes with the top or closing flap in open relation. While many envelopes are shipped to the trade in this condition, there is also a demand for envelopes with the flaps folded to closed position 10 in cases where convenience of packing or other considerations make such folded envelopes desirable.

It is common practice to fold the envelope flaps by hand with the attendant expense when folded envelopes are required.

The present invention has for an object to provide means for automatically folding the flap of the envelope to closed position 20 before delivering the envelope from the machine. A further object is to provide means whereby the closing flap of the envelope may be either creased only or creased and folded before delivery from the machine as 25 desired.

A further object is to provide means whereby an envelope having a closing flap and a foldable locking tongue can be delivered with the flap and locking tongue both 30 folded and the locking tongue secured in folded relation.

The nature and objects of the invention will be better understood from a description of an illustrative embodiment thereof for 35 the purposes of which description reference should be had to the accompanying drawings wherein;

Figure 1 is a sectional view partly diagrammatic showing an arrangement of apparatus constructed in accordance with the 40 invention.

Figure 2 is a detail sectional view taken on the line 2—2 Figure 1 showing the arrangement of pads for applying adhesive 45 to the paper tongue of an envelope of the type having a folded locking tongue.

Figure 3 is a detailed view for the actuating mechanism which controls the gummer 35.

50   Figure 4 is a detail view of the gearing for driving one set of gripping and creasing rolls.

The mechanism shown is intended to 55 form a part of an envelope making machine which mechanism receives the envelope after

the side wings have been folded into overlapping relation and pasted together. The envelope in this condition passes bottom first between the feed rolls 5 to the gripping roll 6 and creasing roll 7 where the 60 bottom flap is folded to form the bottom of the envelope. As the forward end of the flap passes between these rolls adhesive such as gum is applied thereto by a gumming pad 8 carried in the creasing roll 7. 65 The creasing blade 9 cooperates with the gripping member 10 to grip the envelope on a transverse line between the flap and the body of the envelope and continues to grip said envelope on this line as it passes 70 forward. As the flap passes from between the two rolls it is folded part way back by the action of the gripping member and is then engaged by the ends 11 of guides 12 which together with the pressing roll 15 75 operate to fold the flap against the body of the envelope and secure it thereto to form the bottom of the envelope. The envelope thus formed passes between the skid 16 and the guide wires 12 which latter extend 80 through annular recesses in the pressing roll 15 passing forward to the feeding rolls 18, 18, by which it is carried over a skid 20 and between the gripping roll 21 and creasing roll 22 where the gripper 23 cooperates with 85 the blade 24 to crease and grip the envelope on a transverse line between the body of the envelope and the closing or top flap thereof.

If it is desired to deliver the envelopes 90 with this flap open, the envelope is carried along on the face of the creasing roll 21 and between it and the pressing roll 25 which in this case serves merely as a feed roll and from between these two rolls the 95 envelope is delivered to a belt conveyor mechanism 26 of usual type. In order to insure the passage of the envelope to engaging position between the gripping roll 21 and the pressing roll 25, a guide 27 is suitably 100 positioned between the creasing roll and the pressing roll substantially parallel to the gripping roll 21.

When it is desired to fold the top or closing flaps of the envelopes before delivery 105 from the machine, the guide 27 is adjusted to inoperative position and the bottom of the envelope is allowed to pass from between the gripping roll 21 and the creasing roll 22 away from the face of the gripping roll 110

while the gripper 23 is actuated to retain its grip upon the envelope between the body thereof and the closing flap until said gripper passes into engagement with the pressing roll 25 and draws the envelope reversed 5 behind it.

In this operation of the machine the body of the envelope passes out into the space between the pressing roll 25 and the creasing roll 22 while the gripped portion of the envelope is carried between the gripping roll 21 and the pressing roll 25 and the body of the envelope is folded back against the flap, the action of the pressing roll 25 being to 10 complete this folding operation. The envelope is then delivered to the belt conveyor 26 in folded condition with the flap folded against the body thereof.

In the arrangement shown the envelope 20 would ordinarily, if engaged by no guides, pass above the pressing roll 25 due to the direction of its travel between the gripping and creasing rolls and its own stiffness. However, in order to insure the passage of 25 the forward end of the envelope outwardly, away from the gripping roll 21 so that it will not be engaged by the pressing roll, I prefer to provide guiding means arranged to engage the forward or bottom end of the 30 envelope as it passes from between the creasing and gripping rolls. In the preferred arrangement illustrated this guiding means is movable. It may conveniently consist of a guide 30 pivotally mounted concentrically 35 with the creasing roll 22 and adjustable to inoperative position when not to be used. Such a guide member may be cam actuated to move to position closely adjacent the gripping roll 21 to receive the forward end of 40 the envelope as it passes between the rolls and to be then retracted at substantially the peripheral speed of the gripping and creasing rolls until the forward end of the envelope has been carried upward to a position 45 to be received by a guide 32 at which time if desired the guide may be quickly retracted to permit the forward end of the envelope to drop on to the said guide 32. The guide 30 is controlled in its annular 50 movement by a link 31 which is formed as a yoke controlling the shaft 33. This yoke carries a cam pin 31' which engages a cam groove 34 insuring properly timed oscillation of the guide. As the gripping roll continues 55 its rotation with the envelope securely held by the gripper 23, it is carried between the gripping roll 21 and the pressing roll 25 in a manner to reverse the body of the envelope end for end, folding the envelope 60 body back against the flap thereof.

Obviously is is not essential that the guide 30 should be retracted in a manner to entirely free the end of the envelope, nor is it essential that such a guide be provided for 65 the arrangement of the rolls may be such

that the envelope due to its inherent stiffness will pass sufficiently far from the gripping roll 21 before engagement with the pressing roll to avoid being drawn into the space therebetween. The guides 32 may of 70 course be extended to engage the envelope when so passing forward if the guide 30 is omitted.

The apparatus shown is furthermore particularly advantageous in the manufacture 75 of a folded tongue envelope in which closure is effected by means of a flap having a perforation which registers with a perforation in the body of the envelope, the flap being locked in envelope-closing position by means 80 of a tongue passing through the perforations and in which the locking tongue consists of a length of paper folded on itself. An envelope of this general character is shown in the patent to Trenchard 1,171,006 dated 85 February 8, 1916, but in said patent a separate reinforcement is provided instead of folding a long tongue formed as an integral part of the blank. For the purpose of applying adhesive upon such an envelope 90 tongue I provide on the creasing roll 7, an adjustable paper tongue gummer 35. In the arrangement shown for the purpose of illustration the gummer comprises pads 36 carried on a radially movable plunger 37 carried by a hub 38 which is adjustable 95 around the shaft 39 of the creasing roll 7. The gumming pads are arranged to receive gum from a roll 40. For this purpose means is provided for moving the gum pads 100 radially outward a sufficient distance to reach said gum roll 40 at a predetermined point during the rotation of the creasing roll 7. They are also so controlled as to be projected into engagement with the envelope 105 as it passes between the creasing and gripping rolls but during the remainder of the rotation these pads may be retracted so as to lie inside of the exterior face of the roll if desired. In the arrangement shown a cam 110 42 is rotatably mounted on the hub 38 to permit a limited rotative movement. This cam is provided with a cam slot 44 in which a pin 45 projecting from the gummer 37 is 115 engaged. The periphery of the cam 42 is provided with gear teeth which mesh with a pinion 46 on a rock shaft 47. The outer end of the rock shaft 47 carries an arm 48 having a roller 49 engaging the stationary cam 50 secured to the machine frame concentric with the shaft 39. The control arm 48 is normally secured to the rock shaft 47 by means of a set screw 51. When it is desired to readjust the position of the gummer, the set screw 51 is backed off and a set screw 52 holding the hub 38 to its shaft is released. The hub 38 is then rotated to desired position. This causes rotation of the pinion 46 and shaft 47. When the desired position is obtained the set screws are again tightened 120 125 130

to hold the hub 38 to its shaft to secure the 5 gummer in desired position and to secure the control arm 48 to the rock shaft 47 to again render operative the cam control of the cam 41 and the radial movement of the gummer.

When folded tongue envelopes of the type above mentioned are to be made in the apparatus illustrated, the several upper feed 10 rolls and the creasing roll 22 are recessed centrally to avoid interference with the gum applied to the tongue by the tongue gummer 35. The gum will be applied to the envelope as it passes beneath the creasing roll 15 7 and the tongue, lying inside of the closing flap, will obviously be folded by the pressing roll 25 and cooperating creasing roll 21 when and as the flap is folded. The adhesive will secure the two folded parts of 20 the tongue. It is contemplated that envelopes of this type will be delivered with the flaps folded.

The arrangement whereby the bottom flap is creased by one set of rolls and the top 25 flap by another separate set of rolls makes provision for a simple method of adjustment for making envelopes of different lengths. By this arrangement the gripping and creasing rolls 6 and 7 may be geared together to 30 rotate in suitable timed relation relative to each other and the gripping and creasing rolls 21, 22 may also be geared together to operate in suitable timed relation relative to each other, each pair of rolls thus constituting a unit. When it is desired to adjust 35 the machine to make envelopes of different lengths the gearing driving one set of rolls is disconnected and this unit is advanced or retarded as desired, after which the gearing 40 is again connected. For example a driving gear 56 through which one unit is driven may be loosened from its shaft, the unit adjusted and the gear again secured to its shaft by loosening the set screw 57. Provision 45 for adjustment of both units obviously may be made if desired. Such adjustment is made without disturbing the timing of the elements of the unit itself so that the necessary timed relation between the gripping and creasing rolls is maintained. This 50 arrangement provides a particularly simple and efficient method of making the adjustment.

The foregoing description of a selected 55 embodiment is illustrative merely and is not intended as defining the limits of the invention.

I claim:

1. In apparatus of the character described, 60 in combination, a gripping roll, a creasing roll and a folding roll cooperating with said gripping roll at spaced points on its periphery, the gripping and creasing rolls being arranged to crease an envelope blank 65 at its open end between the closing flap

and body thereof as it passes between the rolls, the gripping rolls being arranged to grip the fold, the several rolls being so positioned and arranged that the body of the envelope will be deflected away from the 70 gripper roll between the creasing roll and the folding roll and will be folded back against the flap by the folding roll to deliver the envelope with the flap folded.

2. In apparatus of the character described, 75 in combination, a gripping roll, a creasing roll and a folding roll cooperating with said gripping roll at spaced points on its periphery, and guide means between the creasing roll and the folding roll adjustable to 80 guide an envelope along the gripping roll so that it passes from between the creasing and gripping rolls along the face of the gripping roll and between it and the folding or pressing roll and alternatively adjustable to guide the forward end of the envelope outward from the surface of the gripping roll and into the space between the creasing roll and folding or pressing roll.

3. In apparatus of the character de- 90 scribed, in combination, a gripping roll, a creasing roll cooperating therewith to cause a creasing of an envelope between the flap and body thereof, a pressing roll cooperat- 95 ing with said gripping roll beyond said creasing roll, a guide pivotally supported above the axis of said creasing roll, and means for actuating said guide to advance it to a point adjacent the gripping roll to 100 engage an envelope advancing between the gripping and creasing rolls and to retract the guide as the envelope advances to deflect said envelope outwardly from said creasing roll.

4. In apparatus of the character de- 105 scribed, in combination, a gripping roll, a creasing roll cooperating therewith, to cause a creasing of an envelope between the flap and body thereof, a pressing roll cooperat- 110 ing with said gripping roll beyond said creasing roll, a guide pivotally supported above the axis of said creasing roll, and means for actuating said guide to advance it to a point adjacent the gripping roll to 115 engage an envelope advancing between the gripping and creasing rolls and to retract the guide as the envelope advances to deflect said envelope outwardly from said creasing roll, said cam means being arranged to retract the guide at first slowly to 120 carry the end of the envelope with it and then more rapidly to release the end of said envelope.

5. In apparatus of the character de- 125 scribed, in combination, a gripping roll, a creasing roll and a pressing roll cooperating with said gripping roll at spaced points on its periphery, the gripping and creasing rolls being arranged to crease an envelope be- 130 tween the closing flap and body thereof and

the gripping roll being arranged to grip the fold, and guiding means adjustable to guide the forward end of the envelope either between the gripping and pressing rolls or outwardly to permit reversal of the direction of travel of the envelope between said gripping and pressing rolls.

6. In apparatus of the character described, in combination, a creasing roll arranged to grip an envelope, toward its end, a pressing roll cooperating therewith, at a point advanced peripherally around said gripping roll from the position of gripping operation of said gripping roll and means for deflecting the forward end of the envelope away from the gripping roll to permit it to be turned end for end while gripped by the gripping roll and before passing under said pressing roll.

20 7. In apparatus of the character described, in combination, a gripping roll, means for causing said gripping roll to grip an envelope on a transverse line between the body of the envelope and a flap extending rearwardly therefrom, and means to cause the envelope to be folded back against the flap while still gripped by said gripping roll.

8. In apparatus of the character described, in combination, a roll, a gum applying device carried thereby comprising a radially movable gumming pad, and a rotatable cam associated with said radially movable gummer to move the same radially, a rock shaft carried by said roll, a gear thereon meshing with peripheral gear teeth on said cam, a cam for controlling said rock shaft during the rotation of the roll, a second roll cooperating with the first roll, and creasing and folding devices carried by said rolls and cooperating to crease and fold a blank.

40 9. Delivery mechanism for an envelope machine comprising in combination means to crease the envelope transversely to determine a line of fold for the closing flap and means to deliver said envelope with the closing flap extended or folded against the body of the envelope according as said means are set.

10. Delivery mechanism for an envelope machine comprising in combination means to crease the envelope transversely to determine a line of fold for the closing flap, means to grip the envelope at said line of fold, and means adjustable to deliver said envelope bottom first or to reverse the envelope while still held by the gripping means and to deliver the envelope in reversed position with the flap closed.

60 11. In apparatus of the character described, in combination, a gripping roll, creasing means cooperating with the gripping roll to determine a line of fold for the

closing flap of an envelope and means for causing the envelope to be delivered with the flap open or with the flap folded according as said means are set.

12. In apparatus of the character described, in combination, a gripping roll, creasing means and pressing means cooperating therewith, said creasing means cooperating with the gripping roll to determine a line of fold for the closing flap of an envelope and guiding means for causing the envelope to pass directly to said pressing means or to be reversed while held by the gripping roll and to pass to said pressing means in reversed position with the closing flap folded.

13. In apparatus of the character described, in combination, a gripping roll, means for creasing the envelope transversely to determine a line of fold for the closing flap, said gripping roll being arranged to grip said envelope on said line of fold, and means for reversing the envelope while held by the gripping roll and means for pressing the reversed envelope against the flap.

14. In apparatus of the character described, in combination, a set of gripping and creasing rolls cooperating to fold the bottom flap of an envelope blank and a second set of gripping and creasing rolls cooperating to crease and fold the closing flap of the envelope.

15. In apparatus of the character described, in combination, a roll and means cooperating therewith for creasing an envelope blank to define a bottom flap, a second roll and means cooperating therewith for creasing the blank to define a closing flap, one roll being adjustable peripherally relative to the other to determine the length of the envelope.

16. In apparatus of the character described, in combination, a roll and means cooperating therewith for creasing an envelope blank to define a bottom flap, a second roll and means cooperating therewith for creasing the blank to define a closing flap, means for adjusting one roll peripherally relative to the other to make envelopes of any length within the limits of the machine.

17. In a rotary envelope machine, in combination, a plurality of independent creasing units operable to crease an envelope blank adjacent opposite ends, one of said creasing units being peripherally adjustable relative to the other to make provision for making envelopes of different lengths.

In testimony whereof, I have signed my name to this specification this 9th day of May, 1923.

JAY G. SWAB.
